BOAT PROPULSION

Original Filed May 16, 1932

UNITED STATES PATENT OFFICE

2,007,550

BOAT PROPULSION

Robert E. Tait, Chicago, Ill.

Application May 16, 1932, Serial No. 612,895
Renewed September 8, 1934

5 Claims. (Cl. 115—63)

The present invention relates to boat propulsion and more particularly to an improved form of propelling means therefor.

It is an object of the present invention to provide for a boat a propelling means which, while carrying the boat forward, buoys it to the surface of the water in order that such forward movement will not be retarded by a horizontal component of force impinged against the hull as is inherent to all contemporary form of propulsion.

Another object of the present invention is to provide for the propulsion of a boat a continuously moving means having deflectors thereon adapted to impart simultaneously, downward and horizontal components of force to the water on which the boat rides.

Still another object of the present invention is to lay a continuous track having inclined paddles thereon on the surface of water and to move the track relative to the water at such a speed that the reacting vertical force of the water against the inclined members will keep the track upon the water surface, a boat upon said track supplying locomotion thereto above such water surface.

It is also an object of the present invention to provide for a boat a propelling means which changes the angle of its resultant impellant force to the water.

With these objects and other desirable objects in view, as will be disclosed in the following description, the invention resides in the unique construction and improved combination of its constituent parts as completely illustrated in the accompanying drawing comprising three figures and hereby made a part of this specification, and in which:

Figure 1 is a perspective side view of a boat with the invention attached thereto, the drawing being somewhat schematic;

Figure 2 is a fragmentary side view of a belt for carrying paddles; and

Figure 3 is a sectional view of the belt shown in Figure 2, and taken at the line 3—3 in that figure.

Like reference characters indicate similar parts in the following description which is to be read in conjunction with the drawing.

Attention is first directed to the drawing and particularly to the boat body designated by the numeral 10. This hull may be of any suitable shape, length and beam. Any suitable rudder or steering mechanism may be provided. Along either side of the hull are distributed a plurality of similar idler drums 11 of suitable material.

Transversely positioned near the stern of the boat

10 is a main drive shaft 12 suitably journaled in the boat's side walls and having a drum 13 keyed to each end. Upward of the bow of the boat in the side walls are opposed slots 14 extending longitudinally of the greater dimension of the boat and having slidably stationed therein bearing blocks 15. The journaled members 15 mutually bear a shaft 16 which has a tension drum 17 feathered to each extreme end. A compression spring 18 intermediate the blocks 15 and the rear ends of the slots 14 constantly urges said blocks forwardly in the slots.

All drums on each side of the boat are in alignment. The members 19 bearing the idler drums 11 may be provided in the form of stud shafts projecting from brackets attached to the sides of the boat, or they may be the ends of a long shaft transgressing the entire hull.

Drawn tautly over the drums at each side of the hull is a continuous belt 20. The springs 18 insure tautness of the belts by their resultant forward urge on the drums 17. The belts may be of any desired width. For example, the belts 20 may be of a width greater than that of the boat itself. Each belt 20 may be of any strong flexible material preferably unaffected by being immersed in water, such as heavy duck or canvas with waterproofing thereon. Riveted, or otherwise suitably secured at regular intervals to the outer periphery of the belt 20 are angular plates 21.

The plates 21 may be of sheet metal or of other suitable material to provide a base section 22 co-extensive the width of the belt, an inclined portion 23 bent at an angle to said flange, and a reversed deformation to effect a flange 24; the latter being substantially normal to the inclined portion and terminating in the plane described by said base.

Apertures in the base 22 receive any standard fastening means 25 which pass through complementary apertures in the belt 20 and in registry therewith to secure the angular plates 21 to the belt. The inner end of the rivets 25 may be terminated and protected between laminated sections of the belt 20 that no contact thereof will be had with the rolling faces of the several drums.

The paddles 21 may have a slightly reduced section between the base 22 and the surface 23. The tangential force imparted thereto when being rotated about the pulley 13 will flex the paddle to force the flange 24 from the belt 20, and thereby present the inclined section 23 in more direct contact with the water.

The power received by the drum pulley is transmitted by frictional contact to the belt which in

turn rotates the idler drums 11 and 17. The belt is disposed to move forward in its upper flight and backward at its lower flight which is in contact with the water. An elevated position is provided for the tension idler 17 so that a downward impact will be given the water by the paddles upon first coming in contact therewith, thereby to receive an equal and opposite vertical buoyant force from the water to force the belt to the water surface. Likewise as the paddles are forced rearwardly a vertical component of force F is developed against the inclination 23 to raise the belt to the surface of the water.

It will be noted that the belt assembly is mounted on the boat in a manner that the lower side of the belt depends below the bottom of the hull. If the belt maintains a position on the top of the water as it will do after it has attained a proper speed then there will be a clearance therebetween the surface of the water and the boat hull, as illustrated in the drawing. The figure discloses the water line relative the boat when in motion, and when not in motion. These two water lines are indicated by the reference characters 27 and 28, respectively.

It might appear that for the elevated position of the hull to be maintained there would have to either be a constant acceleration of the speed of the belt or a dragging of the boat hull on the water to impede the forward movement of the entire craft relative the water in order that a "slippage" will continue to occur between the bottom portion of the belt and the water. The small amount of energy required to displace the water from the front of the belt trackage, however, will prevent the speed of the craft attaining that of the belt, hence sufficient "slippage" will be provided at the bottom of the belt to develop the reactionary vertical component of force F_v between the water and the inclined section of the paddles.

Due to the movement of the paddles in the water, there is a resultant force F_n set up at P, the center of area of the inclined section 23, and normal to said section. F_n may be resolved into vertical and horizontal components F_v and F_h respectively. F_n is proportional to the sine² of angle θ , and F_v is proportional to sine θ cosine θ , hence for a given constant "slippage" of the belt 20, the component F_v will be greater when θ equals forty-five degrees, and F_h will be greater with any increase of the angle θ up to ninety degrees. With a heavy boat tending to submerge the belt below the normal operating plane, the inclined plates 21 would be adjusted or replaced with others having an angle θ approximating forty-five degrees. A lighter craft not requiring so great a vertical force may be supplied with inclined members with an angle to the belt of more than forty-five degrees to result in more of the energy being expended for traction.

It is evident that as the boat gains speed there will be an increase of air resistance against the bow to result in more "slippage" than required to maintain the belt upon the water's surface. At this increased speed the tendency of increased "slippage", with a corresponding dissipation of power, is overcome by the paddles passing over the periphery of the driving drum which have their angle θ greatly increased to thereby supply traction to the belt.

Any suitable power plant may be disposed in the hull 10 to impart rotation to the driving shaft at selected speed.

75 Steering of the craft may be had by means of

a rudder in the conventional manner, as previously indicated.

In Figures 2 and 3 is shown a form of belt 30 with a flexible ridge 31. Ridge 31 is preferably of triangular cross section and is coextensive with the inner face of the endless belt 30. By forming grooves within the periphery of the drums 11, 13 and 17 for the ridge 31 to run in, the belt 30 is positively retained upon the drums. Such an arrangement as the ridge 31 obviates the necessity of crowning the drums thus providing for the transverse elements of the belt remaining perfectly straight when passing over the drums. The bases 22 of the detectors, when not distorted by passing over a drum with a crown, do not place any added stress upon the belt due to tugging at the belt fastenings 25.

Having thus described my invention, what I claim as new and desire to secure by Letters Patent is:

1. In a boat propelling means, a sheet of material forming a paddle member and comprising a flat base section, a section extending obliquely from an edge of said base section, and a flange depending from said oblique section and extending into alignment with said base section.

2. For propelling a boat, a continuous belt having a lower flight moving in a substantially horizontal plane while contacting a body of water and a plane-like flight inclined forwardly from said lower flight, a plurality of paddles, each paddle having an inclined face, said paddles being attached to the outer periphery of said belt, and means for moving said belt relative to the boat, movement of said paddles through the water imparting a reactionary force resolvable into horizontal and vertical components upon the inclined faces of said paddles.

3. In a boat propelling device, a paddle comprising a sheet of material having a flat base section, a section extending obliquely from said base, and a flange-like section substantially normal to said oblique section, the material of said inclined section contiguous to said base being resilient to admit of modification in the angular relation of said section and said base.

4. A boat propelling device comprising drums, said drums being arranged one ahead of another and being rotated upon individual horizontal parallel axes transverse of such boat, a continuous belt about said drums for movement therewith, and paddles upon said belt, the foremost of said drums being at an elevation whereby a section of the lower flight of said belt at the front of said boat is declined backwardly therefrom to the next of said drums, the paddles on said belt being spaced one from another at such intervals as to provide for the planing of such declined section against the surface of the water at the front of the boat during movement of the boat.

5. In a boat, a propelling means comprising an endless belt disposed for revolving in a vertical plane parallel to the longitudinal axis of said boat, paddles on said belt, and a rotating means supported in said boat and for carrying said belt so that a lower section thereof makes contact with the water in substantially a horizontal plane while a section to the front of said lower section is inclined forwardly therefrom substantially within a plane, said paddles being spaced at such distances to permit the inclined section of the belt to plane against the water.
